PAIL ATTACHMENT

John Malcolm MacDonald, Portland, Maine

Application May 13, 1936, Serial No. 79,597

5 Claims. (Cl. 220—85)

This invention relates broadly to pails and more particularly to means applicable to a pail in a manner to provide a silencer or sound deadening abutment for the bail or handle of the pail.

In accordance with the present invention a resilient pail silencer is provided and particularly designed for use in hospitals or the like where silence is necessary.

10 The invention together with its objects and advantages will be best understood from a study of the following description taken in connection with the accompanying drawing wherein:—

Figure 1 is a side elevational view illustrating 15 the application of the invention.

Figure 2 is a top plan thereof.

Figure 3 is a perspective view of the silencer per se and

Figure 4 is a perspective view of a clip forming 20 part of the silencer.

Since the pail does not form the essence of the invention only so much of the pail will be positively referred to, and is illustrated, as believed necessary for a proper understanding of 25 the invention. Referring therefore to the drawing it will be seen that 5 indicates generally a portion of the peripheral wall of the pail which pail includes among other parts ears 6 attached thereto near its upper rim and engaging the ends 30 of a wire bail or handle 7.

In accordance with the present invention there is provided for association with each of the ears 6 of the pail a silencer indicated generally by the reference numeral 8.

35 Each silencer 8 is in the form of a body block 9 of rubber or similar elastic resilient material. The body 9 is oblong and has its opposite ends rounded preferably as shown. Further, the block 9 is provided with a slot 10 for receiving a portion 40 of the ear 6, and from one end of the slot to one rounded end of the block said block is slit as at 45 11 to permit the block 9 to be expanded and to permit the block to be slid onto the ear 6 by forcing the block transversely of the ear, the slit 11 thus serving as an entrance slit for the slot 11.

At the slotted end thereof the block 9 has its edge portion provided with a groove 12 for receiving a retaining clip 13.

50 Clip 13 is formed from a single length of wire or other suitable resilient material adapted to fit within the groove 12. At its respective opposite ends the wire 13 is bent laterally inwardly and sharpened to provide penetrating prongs or 55 points 14 that embed themselves within the body

of the block 9 in a manner to secure the clip 13 in position on the body.

As clearly shown in Figures 1 and 2 with the silencers 8 applied to the ears 6 said silencers rest on the upper edge of the wall of the pail and as shown in Figure 1 when the bail 7 is permitted to fall to a horizontal position the pivoted ends of the bail will rest on the block 9 to be supported thereby above and out of engagement with the rim or wall of the pail 5. Also as the bail 7 falls to the dotted line position shown in Figure 1 the pivoted ends of the bail will engage the block 9 which latter will form a sound-deadening support for the bail 7 when the latter is in the dotted line position shown in Figure 1 and thus serves to silence the noise generally accompanying the falling of the bail from a vertical or substantially vertical position to a lowered out-of-the-way position.

It will be therefore appreciated that the silencers or sound-deadening devices 9 may be employed on pails especially those used by attendants in hospitals or the like where silence is necessary and desirable.

It will also be apparent that the block 9 can be cheaply and economically constructed and can be readily applied to the ears 6 or removed therefrom when found desirable.

It is thought that the utility and advantages of an invention of this character will be had without a more detailed description.

Having thus described the invention what is claimed as new is:—

1. The combination with a pail having ears near its upper rim and a bail having its ends engaged with said ears, of a silencer comprising a block of resilient material provided for each of the ears, each block being adapted to rest on the rim of the pail and being provided with a slot through which the upper end of an ear extends.

2. A pail silencer comprising a block of resilient material having a slot therethrough to receive the upstanding end of a pail ear with the block resting on the rim of the pail, and said block being also provided with a slit extending from one end of the slot to one end of the block to facilitate application of the block to the pail ear.

3. A pail silencer comprising a block of resilient material having a slot therethrough to receive the upstanding end of a pail ear with the block resting on the rim of the pail, and said block being also provided with a slit extending from one end of the slot to one end of the block to facilitate application of the block to the pail

ear, and a clip straddling the block at the slit end thereof for holding the block in contracted position on the pail ear.

4. As a new article of manufacture a silencer adapted for application to the ear of a pail and for rest on the rim of the pail, said silencer comprising an oblong block of resilient material provided with a slot and a slit extending from one end of the slot to one end of the block, said block at the slit end thereof being also provided with a groove extending from one side thereof to the other, and a clip engaging in said groove for urging the ends of the block formed by said slit into intimate contact for closing the slot.

5. As a new article of manufacture a silencer adapted for application to the ear of a pail and for rest on the rim of the pail, said silencer comprising an oblong block of resilient material provided with a slot and a slit extending from one end of the slot to one end of the block, said block at the slit end thereof being also provided with a groove extending from one side thereof to the other, and a clip engaging in said groove for urging the ends of the block formed by said slit into intimate contact for closing the slot, and said clip having pointed ends penetrating said block for securing the clip in position on the block.

JOHN MALCOLM MACDONALD.
